UNITED STATES PATENT OFFICE.

HENRY C. HART, OF DETROIT, MICHIGAN.

CALCULATING-MACHINE.

SPECIFICATION forming part of Letters Patent No. 445,447, dated January 27, 1891.

Application filed February 7, 1889. Serial No. 298,996. (No model.)

To all whom it may concern

Be it known that I, HENRY C. HART, of Detroit, in the county of Wayne and State of Michigan, have invented a new and useful 5 Improvement in Calculating-Machines, of which the following is a specification.

This invention relates to calculating-machines, preferably of the type having three graduated dials provided with movable pointers, one of which is moved by a vibrating lever.

The object of the invention is to provide means for varying the stroke of the vibrating lever in proportion to the desired multiplier, and varying the lengths of the arms of the lever in proportion to the desired multiplier. To accomplish this object, my invention involves the features, the combination or arrangement of devices, and the principles of 20 operation hereinafter described and claimed, reference being made to the accompanying drawings, in which—

Figure 1 is a rear elevation of a calculating-machine embodying my invention. Fig. 2 is a similar view showing parts broken away to more clearly exhibit the operating devices. Fig. 3 is a front elevation of the machine. Fig. 4 is a side elevation of the same. Fig. 5 is a detail sectional view showing the pointer-shafts. Fig. 6 is a similar view on an enlarged scale.

In order to enable those skilled in the art to make and use my invention, I will now describe the preferred construction in detail, referring to the drawings, wherein—

The letter X indicates a case or frame, having at the front three concentric dials C, D, and E, each graduated to suit the conditions required and separated by circular slots or 40 spaces in which move the pointers G and E' for the dials D and E. The main portions of these pointers are arranged in rear of the dials C and D, and the intermediate dial D is supported by bridge-pieces c or otherwise. 45 The graduations of the dials are intended to represent the three elements of an operation in multiplication—to wit, the multiplicand, the multiplier, and the product—and I prefer to place the graduations for the product on 50 the outer dial E, which is the indicating or registering dial of the machine.

The graduations of the dial C, Fig. 3, may represent cents or dollars and the graduations on the dial D may represent ounces or pounds, in which event the pointer E' of the 55 indicating or registering dial will indicate the price of a certain number of ounces or pounds at a given price per ounce or pound.

The letter a indicates a rotary shaft, having at its inner end a sprocket-wheel A' and 60 at its outer end portion a pointer F' and a thumb-wheel A, and on this shaft is sleeved a hollow shaft H², carrying at its outer end the pointer G and at its inner end a pinion H'. A hollow shaft G³ is sleeved on the shaft 65 H² and carries at its outer end the pointer E' and at its inner end a pinion G'. A guide-rod J is secured on the back of the case or frame, preferably parallel with the vibrating lever M when the latter is at its highest or 70 initial position, and on the guide-rod, slides a carriage K, the range of motion of which is limited by a stop j, fixed on the guide-rod. An endless metal belt A² runs over the pulleys I I', journaled on shafts in the back of 75 the case or frame, and said belt engages with the sprocket-wheel A'. The belt A² is connected with the carriage K, whereby the motion of sprocket-wheel A' in either direction moves the carriage K along the guide-rod J. 80 A guide-rod L² is secured vertically on the back of the frame, passes up between the guide-rod J and the case or frame, and is encircled at its lower end with a light coiled spring L³, the object of which is to serve as a 85 counterpoise for a light rectangular frame L, which slides vertically on said guide-rod L². The upper side of this frame consists of a channel-bar L⁵, which projects at both sides of the frame L and is set parallel with the 90 guide-rod J, and in this channel-bar runs a slide-block l.

To prevent the frame L from tilting and binding and to hold it at all times in its proper plane, a shaft S is journaled in said 95 frame L and carries at its ends two pinions L⁴ L⁴, which mesh into racks L', secured to the case or frame X, whereby both sides of the frame L are forced to move equally, no matter at what point of the channel-bar the 100 power is applied.

The vibrating lever M is pivoted at M', Fig.

2, to the case or frame of the machine, and a connecting-rod K' is movably fastened by keepers K^3 to the carriage K , the lower end of this rod being connected with said lever M by a roller K^2 , lying in a slot of the lever M . The upper end of the bar K' is connected with the sliding block l , located in the channel-bar L^5 , and the bar K' is shifted along the channel-bar L^5 and lever M by the movement 10 of the carriage K on the guide-rod J . The distance from the fulcrum M' to the roller K^2 , wherever the latter may be in the slot of the lever, constitutes the short arm of the vibrating lever M , and this short arm may be varied 15 from nothing to any point included in the distance from the fulcrum M' to the point M^3 , this point M^3 being the end of travel of the rod K' along the lever. The long arm of the lever is that part from the point M' to the 20 right-hand extremity or free end of the lever, Figs. 1 and 2, on which free end is movably mounted the upward extension m of the uppermost one of two cross-heads T , which slide on vertical guide-rods b^3 , and are connected 25 by a rack b^2 , the construction being such that the motion of the uppermost cross-head T vibrates or oscillates the lever M and permits the slight endwise motion required, from the fact that the lever swings in the arc of a 30 circle, while the cross-head moves in a right line.

A shaft B , journaled in the case or frame, is provided with a thumb-wheel B' and two pinions b b' , the pinion b having the same 35 number of teeth as the pinion H' , and the pinion b' being preferably larger than the pinion b and meshing into the rack b^2 . The rotation of the shaft B causes the rack to rise or fall, and consequently moves the free end 40 of the lever upward or downward.

A double segment H is pivoted to the case or frame, one end meshing into the pinion b and the other end into the pinion H' , so that whatever motion is communicated through 45 shaft B to the pinion b will be exactly transmitted to the pinion H' and pointer G .

A rack G^2 , secured on the side of frame L , meshes into the pinion G' , so that the vertical motion of the frame L moves pinion G' 50 and the pointer E' .

When all the pointers are at zero, the positions of the carriage K , the rod K' , and frame L are as shown in Fig. 1, where the fulcrum M' of the lever M is directly opposite the roller K^2 , at which point the connecting-rod K' is connected with the vibrating lever. The lever M should be, however, at the top of its stroke 55 instead of the bottom, this position being reversed to uncover the parts lying behind and better illustrates the invention. In this position the motion of said lever will not in any way affect the connecting-rod K' , and therefore the lever M is free to move without moving the frame L , so that if the shaft B be rotated 60 the lever M will move and the pointer G will be rotated, but the remainder of the mechanism and pointers will stand station-

ary; but if the shaft a be turned through one-half a rotation the pointer F' is caused to traverse one-half the dial C . This will also 70 rotate the sprocket-wheel A' through half a rotation and move the carriage K one-half its total travel on guide-rod J . The point of connection between the rod K' and lever M will therefore be shifted to a position equal to 75 one-half of the total distance between M' M^3 , and of course the block l will also move an equal distance on its channel-bar. If, as shown in Fig. 3, this causes the pointer F' to stand at the figure "25," it puts the mechanism in such 80 position that any motion given to the pointer G will cause the pointer E' to indicate or register twenty-five times the figure indicated by the pointer G in this manner. Motion of the shaft B causes the pinion b , acting through 85 the segment H , to operate the pinion H' , and thus move the pointer G , while the pinion b' depresses the rack b^2 , which, when the pointer G is at zero, is at its highest point and draws down the free end of lever M , thus 90 drawing down the connecting-rod K' , and with it the frame L . This causes the rack G^2 on the frame L to rotate the pinion G' and move the pointer E' . It is evident that as pinions b and H' are equal the pointer G will 95 move through exactly the portion of a circle through which the shaft B moves. Now if the mechanism through which shaft B actuates lever M is connected with said lever at the point M^3 , which is the ultimate limit of 100 travel of roller K^2 on said lever, as shown in Fig. 2, but is not the point on said lever to which said roller is supposed in this description to stand, such supposed point being half way between M' and M^3 and the pinions b' and G' , each having the same number of teeth. On moving the lever M the roller K^2 will 105 travel one-half as far as the point M^3 travels, and the frame L will be drawn down one-half as far as the point M^3 of the lever M moves, thus moving pointer E' one-half as far as 110 pointer G moves.

Inasmuch as the number of divisions into which the dial E is graduated is the multiple of the highest numbers of the dials C and D , 115 the pointer E' will indicate the multiple of the numbers indicated by pointer F' and G , and this ratio and result will continue however the relative lengths of the two arms of lever M may be varied. In the construction 120 shown in the drawings I have, as a matter of convenience, connected the mechanism by which lever M is actuated to said lever at the free end of the lever or at the point m , which is at a greater distance from the fulcrum M' 125 than is the point M^3 . It follows, therefore, that with this construction the two arms of the lever cannot be equal, and that to compensate for this the mechanism that moves the free end of the lever must be to the mechanism which moves the pointer E' as the distance M' m is to the distance M' M^3 , and I do 130 this by making the pinion b' proportionally greater in number of teeth than the pinion

G' , the teeth on both pinions being of the same size. It is further evident that the relative movement of the free end of lever M and of the connecting-rod K' will vary with 5 the varying distance of the roller K^2 from the fulerum M' of the lever M , and that as this distance is determined by the amount of rotation given to the shaft a the distance between the fulerum M' and the roller K^2 may 10 be varied to suit any desired figure indicated on dial C , and that when this distance has been adjusted the same proportional rate of motion will be imparted through frame L and rack G^2 to the pinion G' and pointer E' by 15 the same motion which carries the free end of the lever through the desired portion of its stroke. It follows, therefore, that the principle of the machine consists in varying the stroke of a vibrating lever in proportion to 20 the desired multiplicand, and varying the relative lengths of the arms of the lever in proportion to the desired multiplier. It is also evident that the form and arrangement of the mechanism which varies the relative 25 lengths of the lever, which actuates the lever, and which is actuated by the lever may be varied widely from that which I have illustrated without departing from the principle of my invention.

30 In the preferred form of my invention, as exhibited by the drawings, the registering mechanism comprises the dial E , the pointer E' , the rod K' , the frame L and its concomitants, the rack G^2 , and the pinion-carrying shaft G^3 , so that such registering mechanism is operated by the vibrating lever. The mechanism for shifting the point of contact of the registering mechanism with the lever (*i. e.*, the contact of the rod K' with the lever 35 40) comprises the thumb-wheel A , the shaft a , the sprocket-wheel A' , the belt A^2 , and the carriage K , moving on the guide-rod J . I would state, however, that I believe myself to be the first to construct a calculating or 45 multiplying machine wherein a vibrating lever continually varies the lengths of its two arms and continually varies its stroke in proportion to the desired multiplier and the desired multiplicand, and therefore I do not 50 confine myself to the specific registering or shifting mechanisms described and shown, for they may be modified or varied without departing from the spirit of my invention.

What I claim, and desire to secure by Letters Patent, is—

55

1. In a calculating-machine, a vibrating lever, mechanism, substantially as described, for moving said lever through any desired portion of its stroke, registering mechanism adapted to be operated by the motion of said lever, and means, substantially as described, for shifting the point of contact of said registering mechanism with said lever, substantially as and for the purposes set forth.

60

2. In a calculating-machine, the combination, with a pivoted lever having one arm connected with actuating mechanism, of an indicator adjustably connected with the other arm, substantially as and for the purposes set forth.

70

3. In a calculating-machine, the combination of a vibrating lever, mechanism, substantially as described, for moving said lever through any desired portion of its stroke and for indicating said movement, means, substantially as described, for varying the relative lengths of the arms of said lever and for indicating said changes, and an indicator adjustably connected with and actuated by said lever, substantially as and for the purposes set forth.

75

4. In a calculating-machine, the combination of three graduated dials, the third having as many divisions as the product of the highest numbers on the other two, and each dial having a movable pointer, a movable lever adjustably connected with the pointer of said third dial, mechanism for moving one of said pointers and proportionally varying the connection between said lever and the pointers of the third dial, and mechanism for simultaneously moving the remaining pointer and said lever, substantially as and for the purposes set forth.

85

5. In a calculating-machine, the combination of the dials C , D , and E , the pointers F' , G , and E' , the lever M , adjustably connected with pointer E' , the shaft a , connected with pointer F' and with the connection between lever M and pointer E' , and the shaft B , connected with lever M and pointer G , substantially as shown and described.
